CLAIM

The ornamental design for an armchair, as shown and described.

DESCRIPTION

Figure 2.1 is a front view of an armchair of the present invention;

Figure 2.2 is a right, front perspective view of the armchair shown in Figure 2.1;

Figure 2.3 is a front, right perspective view of the armchair shown in Figure 2.1;

Figure 2.4 is a left, front perspective view of the armchair shown in Figure 2.1; and

Figure 2.5 is a rear, left perspective view of the armchair shown in Figure 2.1.

1 Claim, 5 Drawing Sheets
